UNITED STATES PATENT OFFICE.

THOMAS F. STONE, OF JACKSBORO, TENNESSEE.

DESIGN FOR A TIRE TREAD.

Application filed May 24, 1923. Serial No. 6,265. Term of patent 14 years.

To all whom it may concern:

Be it known that I, THOMAS F. STONE, a citizen of the United States of America, residing at Jacksboro, in the county of Campbell, State of Tennessee, have invented a new, original, and ornamental Design for Tire Treads, of which the following is a specification, reference being had to the accompanying drawing, forming part thereof.

Figure 1 is a plan view of a portion of a tire tread showing the new design.

Figure 2 is a transverse sectional view.

I claim:

The ornamental design for a tire tread, as shown.

THOMAS F. STONE.
